UNITED STATES PATENT OFFICE.

JULIUS KRUTTSCHNITT, OF CHICAGO, ILLINOIS.

RAILROAD-RAIL SPIKE.

1,069,792.

Specification of Letters Patent. Patented Aug. 12, 1913.

Application filed June 9, 1910. Serial No. 566,005.

To all whom it may concern:

Be it known that I, JULIUS KRUTTSCHNITT, a citizen of the United States, and a resident of Chicago, Cook county, Illinois, have 5 invented certain new and useful Improvements in Railroad-Rail Spikes, of which the following is a full, true, clear, and exact description.

My invention relates to improvements in 10 spikes and has particular reference to rail spikes for securing railroad rails to wooden cross-ties.

The object of my invention is to provide a rail or track spike which shall be so 15 formed that while it may be quite easily driven into a cross-tie, it will be firmly retained therein and may be withdrawn only by the exertion of great force.

A further object is to provide a railroad 20 spike so formed that any force applied to withdraw the spike will tend to increase the hold of the fibers of the tie upon the spike.

My invention consists in a railroad or track spike having a shank of substantially 25 rectangular cross section and having in one or more of its longitudinal faces, a longitudinal groove or slot of substantially uniform depth but tapered longitudinally and wider at its upper than at its lower end.

The invention also consists in a railroad 30 spike the opposite shank faces of which are provided with shallow, substantially trapezoidal grooves, the bottom walls of said grooves being parallel and said grooves being tapered and wider at their upper ends than at their lower ends.

It further consists in a track spike having 35 a rectangular shank, a head on one end adapted to engage a rail flange, and a V-shaped point on the other end adapted to sever the fibers of a cross tie, the front and rear faces of said shank being provided with shallow longitudinal grooves extending from the point and ending adjacent to the head, 45 the bottom walls of said grooves being parallel, said grooves being tapered and narrower adjacent to the point than adjacent to the head of the spike, and transverse shoulders on said bottom walls.

It further consists in a track spike having 50 a substantially rectangular body portion, longitudinal grooves on the front and rear faces of said body portion, the bottom walls of said grooves being parallel, said grooves being narrower at their lower ends than at their upper ends, and transverse shoulders

on said bottom walls and on the side faces of said body portion.

My invention also consists in the features of construction and combinations and relations of parts whereby a railroad spike of exceptionally great holding power is produced, all as hereinafter fully described and particularly pointed out in the claims.

My invention will be more readily understood by reference to the accompanying drawings forming part of this specification and in which:

Figure 1 is a front elevation of a track spike illustrating a suitable embodiment of 70 the preferred form of my invention; Fig. 2 is a side elevation partly in vertical section of the spike illustrated in Fig. 1; Fig. 3 is a side elevation of a spike showing a modification of the invention; Fig. 4 is a horizontal sectional view on the line 4—4 of Fig. 2; Fig. 5 is a similar section on the line 5—5 of Fig. 3; Fig. 6 is a similar section illustrating a second modification of the invention; Fig. 7 is a section similar to Fig. 80 4, but showing an additional modified form of the invention; and Fig. 8 is a fragmentary vertical section on the line 8—8 of Fig. 6.

The preferred form of my invention as 85 illustrated in Figs. 1, 2 and 4 comprises the body portion or shank 1, having the head 2 on one end and the V-shaped point 3 on the other end. The head 2 is similar to the usual track spike head having the forwardly projecting portion 4 adapted to overlap and to engage a rail flange and the laterally projecting flanges 5 by means of which the spike may be withdrawn from a cross-tie. The V-shaped point is formed by two upwardly and 90 outwardly inclined surfaces 6 and 7 forming the cutting edge 8 on their meeting line. This cutting edge 8 is adapted to sever the fibers of the tie when the spike is driven thereinto and the inclined surfaces 6 and 7 100 spread the ends of the severed fibers curving them downward to a slight degree and placing them in position to act as struts or braces against the forward and rear faces of the body of the spike and thus retain the 105 spike in the tie.

The front and rear faces of the spike are provided with longitudinal grooves 9 extending from the inclined surfaces 6 and 7 and ending adjacent to the head 2 of the 110 spike, in other words they extend the effective length of the body portion of the spike.

Said grooves 9 are substantially trapezoidal in cross section and uniform in depth and consequently the bottom walls 10 thereof are parallel with each other. The grooves 9 are 5 preferably narrower at their lower ends or adjacent to the point of the spike than at their upper ends or adjacent to the head of the spike. This construction results in the grooves being tapered longitudinally of the 10 spike and adapted, when an attempt is made to withdraw the spike from the tie, to compress the ends of the fibers laterally, which lie within the grooves. This action of the grooves upon the fibers tends to wedge 15 the fibers within the grooves and cause additional friction upon the body of the spike and thus prevent its easy withdrawal. The bottom walls 10 and side walls 11 of the 20 grooves 9 are provided with a plurality of shallow concave transverse grooves 12. The grooves 12 are arranged close together and completely cover said walls forming transverse shoulders 13 therebetween. The inclination of the upper surfaces of the ridges or 25 shoulders 13 is such that they present abutment surfaces substantially at right angles to the end of the curved fibers of the cross- tie.

As the spike is driven into the tie the 30 chisel edge 8 severs the fibers of the tie, the inclined surfaces 6 and 7 spread the fibers apart and the shoulders 13 receive the severed ends, the fibers acting as struts or braces upon the shoulders 13 to retain the spike in 35 the tie.

I sometimes prefer to dispense with the transverse shoulders, forming the grooves 16 with their bottom and side walls smooth, as shown in Figs. 3 and 5. In this form I 40 rely upon the wedging action of the tapered longitudinal grooves and the friction caused by the compressive force of the fibers of the tie upon the body of the spike to retain the spike in the tie against the forces tending 45 to withdraw it.

In addition to the longitudinal grooves 9 in the front and rear faces of the spike, I sometimes provide the side faces of the body portion of the spike with shallow concave 50 transverse grooves 14 similar to the grooves 12 on the bottom walls of the longitudinal grooves 9. This results in the side walls being provided with transverse or horizontal shoulders or ridges 15 adapted to engage the 55 adjacent fibers of the tie and thereby aid in retaining the spike in the tie.

The grooves 9 are so proportioned in depth to the whole thickness of the spike that the fibers which are spread thereby are not distorted beyond their elastic limit but are rather distorted or curved downwardly just enough to develop their maximum or greatest holding power.

It is obvious that as the two longitudinal 65 grooves perform their functions independ-

ently of each other, either one of them may be omitted without departing from the spirit of my invention. When I do omit one of the grooves, I prefer to omit the one from the forward face of the spike (see Fig. 7) 70 as the tendency of the forces acting upon the spike both when it is being driven and afterward, is to force the spike backward into the tie. When this occurs the groove and ridges on the forward or rail face of the 75 spike are forced out of contact with the severed ends of the fibers and are of no practical advantage and may be dispensed with. As the longitudinal grooves do not reduce the effective depth or thickness of the 80 spike in the direction in which the forces acting thereon tend to bend it, that is from front to rear, its strength to resist such bending is not reduced appreciably while at the same time it is made somewhat lighter 85 in weight.

Having thus described my invention, I claim as new and desire to secure by Letters Patent:

1. A railroad spike comprising a body portion of substantially rectangular cross-section, a head on one end adapted to engage a rail flange and a chisel edge on the opposite end adapted to sever and bend the fibers of the tie when the spike is driven, the front 95 and rear faces of said body portion each being provided with a longitudinal groove extending from the point of the spike and ending adjacent to the head thereof, the bottom walls of said grooves being substantially parallel, said grooves being tapered 100 longitudinally and wider at their upper than at their lower ends and outwardly and downwardly inclined transverse abutment shoulders on the bottom and side walls of 105 said grooves.

2. A railroad spike comprising a body portion substantially rectangular in cross section, a head on one end adapted to engage a rail flange, and a chisel edge on the opposite end adapted to sever and curve downwardly the fibers of the tie when the spike is driven, the forward and rear faces of said body portion each being provided with a shallow longitudinal groove open at its 115 lower end extending substantially the length of the spike and tapered laterally from end to end being wider at its upper than at its lower end, the bottom walls of said grooves being substantially parallel, concave transverse grooves forming shoulders on the bottom and side walls of said grooves and transverse shoulders on the side faces of said body portion.

3. As an article of manufacture, a track 125 spike having a flat bottomed longitudinal depression open at its lower end in one of its sides, said depression being narrower at its lower than at its upper end and a plurality of comparatively small concave transverse 130

grooves in the bottom of said depression forming a plurality of outwardly and downwardly inclined fiber abutment surfaces within said depression, below the face of the 5 spike.

4. As an article of manufacture, a track spike having longitudinal depressions in opposite faces, said depressions being relatively shallow and substantially uniform in 10 depth throughout their extent and narrower at their lower than at their upper ends, and provided with a plurality of comparatively small concave transverse grooves on their bottom walls which present a plurality of 15 outwardly and downwardly extending fiber abutment surfaces.

5. As an article of manufacture, a track spike having longitudinal depressions open at their lower ends in opposite faces, said 20 depressions being substantially uniform in depth throughout their extent and narrower at their lower than at their upper ends and having the surfaces of said depressions divided into a plurality of comparatively 25 small transverse fiber abutment surfaces disposed angularly with respect to the axis of the spike and inclined outwardly toward the point of the spike.

6. As an article of manufacture, a track

spike having longitudinal depressions in opposite faces, said depressions being substantially uniform in depth throughout their extent and wider at their upper than at their lower ends, the bottom and side walls of said depressions having a plurality of 30 comparatively small substantially parallel surfaces inclined downwardly and outwardly; said surfaces being vertically concaved, substantially as described.

7. A railroad spike having a substantially 40 rectangular shank, the front and rear faces of which are each provided with a longitudinal groove substantially trapezoidal in cross section, uniform depth, laterally tapered from end to end and wider at their 45 upper than at their lower ends, the bottom walls of said grooves each being provided with transverse concave grooves closely arranged and forming transverse concave outwardly and downwardly inclined fiber-abutment shoulders, substantially as described. 50

In testimony whereof, I have hereunto set my hand, this 3d day of June, 1910, in the presence of two subscribing witnesses.

JULIUS KRUTTSCHNITT.
